UNITED STATES PATENT OFFICE

2,457,288

FREQUENCY SHIFT KEYING

George L. Usselman, Port Jefferson, N. Y., assignor to Radio Corporation of America, a corporation of Delaware

Original application February 11, 1944, Serial No. 521,907. Divided and this application February 7, 1946, Serial No. 646,069

7 Claims. (Cl. 250—8)

1

This invention concerns frequency modulation and in particular an improved method and means of communication by frequency shift or spaced wave keying. This application is a division of my United States Application Serial #521,907, filed February 11, 1944. By this method of communication carrier wave energy keyed from a first to a second frequency and vice versa is produced. The first frequency may represent marking condition while the second frequency may represent spacing condition. The carrier wave energy so keyed may be considered as originating from a single source the frequency of which is alternately keyed or may be considered as separate carriers alternately translated, the alternation being in accordance with signals such as, for example, telegraphy, facsimile, code or television.

At the receiver both frequencies, that is, the mark and space or first and second frequencies are used in reproducing the signal, thus giving the benefits of positive action on mark and space, the benefit of frequency diversity, etc.

The use of two frequency sources for frequency shift keying as described above has been disclosed in the art, as has been the use of the mark and space frequencies at the receiver. However, method and means known heretofore for accomplishing the keying of the two carrier waves resulted in amplitude keying thereof with all its attendant disadvantages. In the prior systems, even if amplitude keying were not present or did not accompany the frequency shift keying the change from the first to the second frequency is so abrupt that there results a wide dispersion of the side frequencies. This extends the channel, causes overlapping of side bands and produces keying clicks, etc., in the circuits.

An object of the present invention is improved frequency shift keying. An additional object of the invention is improved frequency shift keying without amplitude modulation of the keyed wave, so that in effect the keying from the first frequency to the second frequency is smoothly carried out, thereby reducing the side band frequency spectrum, reducing keying shocks, etc.

In attaining the above objects I use two constant frequency sources, but a method and means is included for the frequency shift keying that holds the amplitude keying modulation to a minimum and also prevents sudden frequency changes. My method and means thereby prevents unnecessary widening of the frequency band. Thus the present frequency shift system retains the advantage of accurate fixed frequen-

2

cies for the mark and space characters of the prior art, but none of the disadvantages.

In describing my invention in detail, reference will be made to the attached drawings, wherein Fig. 1 is a block diagram illustrating schematically the general arrangement of a spaced wave keying system arranged in accordance with my invention.

Fig. 2 illustrates diagrammatically the essential 10 elements of a practical spaced wave keying system such as illustrated schematically in Fig. 1. In Fig. 2, two crystal oscillators are arranged to be continuously operable at the substantially fixed first and second frequencies and to in turn 15 alternately operate through an electronic and mechanical switching arrangement to synchronize a third oscillator producing the controlled space and mark frequencies. The third oscillator is of the regenerative type. A third stabilized oscillator operating at the carrier frequency may also entrain the third oscillator when the same is not entrained by one of the two first mentioned oscillators.

Fig. 3 is a modification of the arrangement of 25 Fig. 2, wherein the lower half of the electric switch tube V3 and the source 20 are omitted.

Fig. 4 is a modification of the arrangement of Fig. 2, and

Fig. 5 illustrates a modified form of controlled 30 generator which may be substituted for the generators of the prior figures.

Referring now to Fig. 1, two crystal oscillators 10 and 20 are provided, one for the mark frequency and the other for the space frequency. 35 The energies from these two crystal oscillators are delivered to the switching circuits and mechanism in 40. The switch in 40 may, as will be seen hereinafter, provide some amplifying effect. The switch in 40 is controlled by the signal from source 30 and as is known, this signal comprises electrical energy representing mark and electrical energy representing space, so utilized that first one crystal oscillator output then the other is switched on or through to deliver crystal controlled excitation to a controlled or synchronized oscillator in 50. The oscillator in 50 may, when uncontrolled, operate at a frequency intermediate mark and space, but is of a nature such that it is smoothly pulled into synchronism by whichever source 10 or 20 is switched through at 40 under the control of signals at 30. The mark and space frequency energy is then amplified and/or frequency multiplied in 60 and utilized say, for example, radiated.

The oscillator 50 is of a type that while it oscil-

lates continuously it is easily controlled and synchronized by either of the crystal controlled oscillators switched on by unit 40. Oscillator 50 is adjusted so that during the intervals of switching it continues to oscillate on a mean frequency with substantially no change in amplitude. The output of controlled oscillator unit 50 is next amplified and/or multiplied in frequency in unit 60 and then radiated by the antenna. The oscillator in 50 is arranged so that it maintains a substantially constant frequency output by self-excitation but readily changes its frequency to synchronize with that of the crystal excitation switched on by the signal from 30 through unit 40.

It can be seen that the oscillator 50 provides a buffer or in effect a fly-wheel between the two crystal oscillators 10 and 20, and the transmitter amplifiers and/or frequency multipliers in 60. The action is two-fold. The oscillations continue at the mean frequency and at substantially constant amplitude during the time when neither crystal is in control, thus the receiver has a carrier to operate on continuously. The second action is that several cycles of oscillation in unit 50 occur during the time of frequency change from mark to space and vice versa. Thus the keying is smooth since the time frequency change is not too sudden and side frequencies are not spread so far. Note that actually in my system three frequencies are involved, these frequencies being mark, space and no signal.

In Fig. 2, V1 is an oscillator of a modified Hartley type having its anode coupled to its screen grid by a tuned LC circuit including condenser CT and inductance L1 with a point on the inductance L1 connected to the cathode by coupling condenser O. Oscillations are generated in the tube V1 and circuit CT, L1 by virtue of the fact that enough electrons are drawn past the control grid at all times to support oscillations. The condenser N is a feedback or regeneration control condenser and 25 is a resistance in shunt to this condenser by means of which positive bias is supplied to the screen grid of tube V1. The anode derives direct current potential from the main source of direct current.

The control grid of tube V1 is connected to the cathode by potentiometer resistance 27 and also by a potentiometer resistance 29, a point of which is coupled by resistance 31 to the positive terminal of the direct current source. The purpose of potentiometer 29 is to adjust the bias as desired on the control grid of this tube. The potentiometer 27 has two taps thereon and provides a means for applying the synchronizing or controlling voltage to the generator of tube V1. Any excitation applied to the control grid or any tube element of the oscillator tube V1 will have a tendency to control the frequency of oscillations generated in tube V1, thereby synchronizing the same with the controlling potentials, provided the natural oscillating frequency of the tube V1 is not too far different from the excitation or control frequency. A controlled oscillator of this general type has been shown and described in detail in Fig. 3 of Usselman Patent No. 2,425,165 dated August 5, 1947. Moreover, the oscillator while stabilized as to a particular frequency is readily swung under control of the synchronizing oscillations about this particular frequency, to which it is tuned, by the signals operating on the switch.

In my improved system a tap on the potentiometer resistor 27 is coupled to the anodes of the tubes V2 and V3, by way of direct current block-

ing and alternating current coupling condenser O5.

Tubes V2 and V3 work in the amplifier and switching circuit which may be included in the switching unit 40 in Fig. 1. The anodes of tubes V2 and V3 are connected by a radio choke L3 to the positive terminal of the main supply source. In this modification the generator at V1 is controlled by oscillations from 10 or 20 through the switching means including tubes V2 and V3. Note that the positive terminal of the direct current source is connected to the screening electrodes of tubes V2 and V3 by the relay contacts 21, 22 and 23. This connection includes a potential adjusting potentiometer 35 which adjusts the amount of positive bias potential applied to the screen grids of keying tubes V2 and V3. The screen grid electrodes of tubes V2 and V3 are connected by resistances R7 and R8 respectively, to the negative terminal of a source E1, the positive terminal of which is grounded. The screen grids of tubes V2 and V3 are also connected by radio frequency bypassing condensers C to the cathodes.

The crystal controlled oscillators in units 10 and 20 are coupled by coupling condensers 15 and 16 to the control grids of the tubes V2 and V3 while low radio frequency potential points on both of the crystal oscillators in units 10 and 20 are connected to ground and to the cathodes of tubes V2 and V3 by a resistance R9 shunted by a coupling and bypassing condenser O. Direct current grid circuits for V2 and V3 are completed through the resistances R10 and R11.

The signal source at A which may be unidirectional currents or potentials of opposite or reversible polarity representing mark and space respectively are supplied to the winding of a relay RE having an armature 21 cooperating with two contacts 22 and 23 to connect the positive terminal of the direct current source to the screen grid of tube V2 or to the screen grid of tube V3 by way of resistance 35 and one or the other of contacts 22 or 23, depending upon whether mark or space signal is being supplied from source A.

The frequencies of the oscillations developed in 10 and 20 are usually made to have the desired prescribed frequency difference of about 100 or more cycles depending upon the needs of the particular system at hand. The relay RE is operated from the signal source A. The relay contacts 21, 22 and 23 alternately change the screen grid bias potentials of the switching and amplifying tubes V2 and V3 from a negative to a positive value. When contact 22 or 23 is closed the screen grid of tube V2 or V3 depending upon which contact is closed is connected to the positive terminal of the source. This alternately switches excitation from crystal units 10 and 20 on the oscillator stage tube V1 because the oscillations are amplified or repeated through one of the tubes V2 and V3 and supplied to the control grid circuit of tube V1. In the mid position of the relay RE negative bias is applied to both switching tubes V2 and V3 from source B through the resistors R7 and R8. In this condition no excitation from either crystal oscillator 10 or 20 is allowed to pass through the amplifying and keying stage. During this time oscillator V1 is operating on its frequency determining circuit CT, L1 and N, unless otherwise controlled or entrained. In this embodiment a mid-frequency oscillator of substantially fixed frequency at 70 supplies oscillations by coupling condenser 19 to 75 a point on the potentiometer resistance 27, con-

nected to the grid of tube **V1** to entrain this oscillator to operate at the mid-frequency or no signal frequency, when relay **RE** is in its mid-position.

Now assume that the signal from **A** closes the relay contacts **21** and **23**. Positive bias is applied to the screen grid of amplifying and switching tube **V2**, which repeats and possibly amplifies the excitation from crystal oscillator **10**, impresses it on the control grid of oscillator tube **V1** through potentiometer **R6**. Since the oscillator **V1** is as described above, somewhat flexible in operation, it has its frequency "pulled" so that it synchronizes with the frequency of crystal oscillator **10**. This new frequency is now transmitted and may represent space or mark. When the signal from source **A** reverses the relay **RE** changes and closes contacts **21** and **22**. During the changeover period there is a short interval of time when negative bias is applied to both tubes **V2** and **V3**, and the excitation from both crystal oscillators **10** and **20** is cut off. Then the oscillator **V1** swings smoothly back towards its own frequency of operation, that is, mid-frequency. When the relay contacts **21** and **22** are closed positive bias is applied to the switching tube **V3** which repeats and possibly amplifies the excitation from the crystal oscillator in **20**, impressing it on the control grid of oscillator tube **V1** to thereby pull its oscillations into synchronism with the oscillations of the crystal oscillator in **20**.

A feature of my present invention is that the oscillator **V1** and the oscillations generated thereby are not synchronized instantly with the oscillations produced by units **10** and **20**. It may take several cycles of oscillations from **10** and **20** before the oscillations developed in tube **V1** are locked in synchronism. By adjusting the potentiometer **27** the amount of control excitation potentials from the crystal oscillators in **10** and **20** to the controlled oscillator **V1** may be set to give the desired "pull-in" or synchronizing time. The effect is a rounding off and slope in the signal characters. Reducing the excitation voltage will increase the rounding and slope of the signal characters. Too much reduction will cause loss of signal or erratic operation. If a large amount of excitation is impressed on oscillator tube **V1** from the keying tubes, the signal characters will be more square shaped at the corners and more side frequencies will be generated. During the shifts in frequency the output of oscillator **V1** remains substantially constant in amplitude.

Although, as pointed out above, the shift between mark and space frequencies is smoothly carried out, it must be understood that the action is positive under all circumstances provided, of course, sufficient control is applied at **27** to synchronize the oscillator **V1** with one or the other of the sources in **10** and **20**. The action is positive because when tube **V3** is keyed on, that is, has its screen grid connected to the positive source of direct current by contacts **21** and **22**, tube **V2** is shut off due to the fact that its screen grid is connected by resistance **R7** to the negative terminal of source **B**.

In the amplifying and switching circuit, **R9** is a potentiometer and a point thereon is connected by a resistance **17** to the positive terminal of the main direct current source. This permits me to raise the cathodes of tubes **V2** and **V3** positive with respect to the grids which are connected to ground by resistances **R10** and **R11**. This provides a means of maintaining a fixed bias on tubes

V2 and **V3** which is necessary to obtain definite cut-off of the current in these tubes.

Potentiometer resistance **27** is a means for adjusting the amplitude of the control voltages on the grid of **V1**, while potentiometer resistance **R9** and resistance **35** are means for adjusting the bias on tubes **V2**, **V3**.

In operation oscillations from **10** of substantially fixed frequency and of a frequency which is desired as a mean or non-signal frequency are supplied to a point on **27** below the point on **27** at which the anodes of tubes **V2** and **V3** are coupled. The oscillator **V1** generates oscillations of a frequency determined by **CT** and **L1** which is preferably the same as the frequency of the oscillations developed in **10**. In any event, **V1** is controlled to operate at the desired mean frequency. Now as the switching tubes **V2** and **V3** are controlled by the reversed current signals from source **A** through relay **RE** the tube **V2** or **V3** (one thereof being cut off as described above) amplifies oscillations from the crystal oscillator **10** or **20** and supplies them by coupling condenser **05** to the point on **27** to control or entrain the oscillations developed in **V1** on marking or spacing frequency.

The respective control actions are adjustable by adjusting the grid bias of tube **V1** and the excitation voltage fed to the grid from **10** or from tubes **V2** and **V3**. Note that the oscillator at **10** is tapped down on resistance **27** as compared to the point on **27** at which tubes **V2** and **V3** are coupled. In the absence of mark and space, oscillator **10** controls the frequency at which the generator **V1** operates. **V2** or **V3** takes over control when mark or space is applied. The excitation of the grid of **V1** by the output of **V2** or **V3** therefore is made stronger than the excitation of the grid of **V1** by oscillations from oscillator **10**. The feedback through **N** is such that oscillations are generated continuously in the tube **V1** of a frequency determined by **CT** and **L1**. The control voltages applied at **27** act on the electron stream to entrain the generated oscillations.

The condensers **C** connecting the keyed screen grid electrodes of tubes **V2** and **V3** to the cathodes of the respective tubes in Figs. 2 and 4 and the condenser **C1** connecting the screen grid of the tube **V2** to the cathode in Fig. 3 are bypass condensers for voltages of radio frequency such as generated in sources **10** and **20**, but these condensers are not to be so large as to distort audio frequency characteristics, otherwise the keying impulses of higher frequency might be greatly reduced in amplitude. However, these condensers may be made as large as .1 mf. or .3 mf. for the purpose of rounding off the signal characters if very high keying speeds are not used. In the prior figures and in Fig. 3, to be described herein-after, the letter **O** is applied to condensers such as between **L1** and the cathode in Fig. 2, which serve primarily as bypassing condensers but may also serve as blocking condensers. These may be of relatively large capacity such as .01 to .1 without doing any harm, and depending on the operating frequency.

As stated above, the arrangement of Fig. 3 is a modification of the arrangement of Fig. 2. Note in general, that if the tube **V3** and source **20** of Fig. 2 were omitted the result would be an embodiment substantially as illustrated in Fig. 3.

In Fig. 3 the crystal oscillator **7** is operating at say the spacing frequency, while the oscillator **10** operates at the marking frequency. The controlled oscillator **V1** which with respect to the

oscillation generator is as in Fig. 2, is set to operate at a frequency slightly above the spacing frequency at which source 7 operates. The source 7 has one terminal connected to ground and the other terminal coupled by condenser 19 and potentiometer resistance P2 to ground. The anode of tube V2 is coupled by coupling and blocking condenser O5 through a potentiometer resistance P1 to ground. The cathode of tube V1 is connected to ground by a cathode resistance 9 shunted by a radio frequency bypassing condenser O. This condenser is of the same general size as the condenser O, described hereinbefore. The control grid of tube V1 is coupled by a resistance and a tap P3 to a point on potentiometer P2 and by a resistance and a tap P4 to a point on the potentiometer P1.

The relay RE has its actuating winding connected to a source of reversible current A as in Fig. 2, but now has its armature 21 biased by a spring SP and connected by a resistance 75 to the direct current source. The screening electrode of tube V2 is connected by resistance R7 to the negative end of source B as in Fig. 2, or by contact 22 to the armature 21 and thence through resistance 75 to the positive terminal of the direct current source. The control grid of tube V2 is biased by source B through resistance R10.

The potentiometers P1 and P2 and the points thereon and the intensity of the source 7 and the gain through switching tube V2 etc., are so arranged that the oscillator V1 is lightly controlled by and synchronized with oscillations from the source 7; that is, the space frequency. When the contacts 21 and 22 of relay RE are closed by pulses in A, the negative bias on the tube V2 from source B is overcome by positive potential supplied through resistance 75 from the main source and the tube V2 amplifies the oscillations applied to the grid from source 10' and feeds to the control grid of tube V1 by way of potentiometer P1 and tap P4 the excitation voltage of the marking frequency. This marking excitation is made considerably stronger than the spacing excitation so that the controlled oscillator tube V1 will now be controlled by and synchronized with the marking frequency of source 10' rather than the spacing frequency in source 7. When the keyed impulse out of A falls the field of the winding in RE becomes weaker, the spring SP moves the armature 22 from contact 21 thereby removing the positive potential from the screen grid of V2 which is cut off and the source 7 again takes control to operate V1 at the spacing frequency.

It is obvious that the embodiments described hereinbefore may be modified in many ways and many other circuit arrangements may be made to carry out the invention. For instance, in Fig. 2 the source 70 may be omitted if one of the keying tubes, say V3, is arranged to not key but instead to pass continuously an adjustable small amount of excitation voltage from the crystal oscillator in 20 to the grid of the controlled or synchronized oscillator in the tube V1; this frequency out of 20 could be used as the spacing frequency. Then when tube V2 is keyed to amplify oscillations from the source 10 a larger amount of marking excitation from this source 10 is applied to the control grid of tube V1 to take control and synchronize the oscillator V1 with the marking frequency out of source 10. When the relaying contacts 21 and 23 open then oscillator V1 drifts back to the space frequency of operation, that is, the frequency generated returns to synchronism with the frequency of oper-

ation of the source in 20. The arrangement of Fig. 4 may be so operated.

Again referring to Fig. 3, if the point P3 on potentiometer P2 is set at the bottom so that no excitation is obtained from source 7, then the natural oscillations of oscillator V1 will be the space frequency and when the mark frequency from source 10' is switched on through tube V2 the oscillations of tube V1 will be synchronized with it. In this way, by adjusting oscillator V1 the spacing frequency may be set about or below the mark frequency as desired. Also the natural oscillations of circuit V1 may be used as the mark frequency and the crystal controlled frequency may be used as the spacing frequency.

The embodiment illustrated in Fig. 4 is a modification of the arrangement of Fig. 2. In Fig. 4, the crystal oscillator 70 of Fig. 2 and its coupling to the oscillation generator including tube V1 is omitted. The anodes of the keying tubes V2 and V3 which in other respects are similar to the arrangement in Fig. 2, are coupled by the coupling condenser O5 to ground through the potentiometer resistance R1 and a point on this resistance is coupled through a coupling condenser 15 to the second grid in the tube V1.

As to the oscillation generator the tank circuit CT, L1 is coupled between the control grid and the anode. The control grid is biased by a resistance 79 and the strength of oscillations or regeneration is established as in the prior figures by adjustable regeneration condenser N. The remaining portions of the circuit and the operation thereof are believed evident from the prior description and from the drawings. The embodiment of Fig. 4 was found to operate very favorably for the purpose designated, that is, generation, control and transmission of frequency shifted currents.

The controlled generator including tube V1, of all of the embodiments may include frequency stabilizing means if desired. The controlled generator of say Fig. 4 is then arranged as shown in Fig. 5. Grid leak resistor 80 and plate supply resistor 82 are in effect each connected across one-half of the tank condenser CT. These resistors also shunt the grid and anode tube resistance. 80 and 82 are made to have approximately equal resistance value, which is small relative to the tube resistances. Those used in one embodiment were 10,000 ohms each. A lower resistor value would work better but the oscillator would also give less output. Coils of the value L2/2 were also connected at the locations marked by X between the ends of the tank circuit CT, L2 and the condensers 86. This gave a small amount of improvement.

Referring again to Fig. 5, it may be stated that the condensers marked O5, 75, 86 and 87 are low impedance bypass condensers. It is known to the art that if a resistance is connected across a tuned circuit a variation of the total resistance, such as that which would be caused by temperature change, does not change the resonant frequency. Also since 80 and 82 are small compared with the tube resistances a variation of tube resistance, such as that caused by voltage changes (tube current changes) and the like have very little effect on the oscillator frequency. The capacity changes also have small effect on the operating frequency, especially when the L2/2 coils are used in the connection indicated by X. It should be noted that these frequency stabilizing means can be applied to any of the circuits of this invention.

It was also found that, by making the capacity of condenser CT relatively larger and by making the inductance of coil L1 or L2 relatively smaller than that generally used, the changes of capacity and resistance of tube VI have a much less effect on the frequency of the oscillator circuit. Since the frequency deviation used for frequency shift keying is relatively small, stiffening the tank circuit by the use of a larger condenser and a smaller coil caused no difficulties in modulation, in fact improving the "fly-wheel" effect of the oscillator. Of course CT and L1 or L2 should be made of materials that will cause minimum changes of capacity and inductance with changes of temperature or humidity.

What is claimed is:

1. In a signalling system a source of oscillations of controllable frequency, a source of oscillations of a first and substantially fixed frequency coupled thereto, a source of oscillations of a second and substantially fixed frequency, a source of oscillations of a third and substantially fixed frequency, and a switching device controlled in accordance with signals for alternately coupling said second and third sources of substantially fixed frequency to said source of controllable frequency for controlling the frequency of the oscillations generated in said source of controllable frequency in accordance with signals.

2. In a signalling system, a tube generator of oscillations of controllable frequency, a source of oscillations of substantially fixed frequency coupled to said generator for entraining operation of the same, a second source of oscillations of a second and substantially fixed frequency, a third source of oscillations of a third and substantially fixed frequency, and a pair of switching tubes controlled in accordance with signals for alternately coupling said second and third sources of substantially fixed frequency to said source of controllable frequency for entraining the same with one or the other of the second or third substantially fixed frequency sources.

3. In a signalling system, a controllable oscillator operating at a first frequency, three control oscillators operating respectively, one substantially at said first frequency, another at a frequency above, and the third at a frequency below said first frequency, and means controlled by signals for coupling at least one of the control oscillators to the controllable oscillator to entrain the same to operate at the frequency of operation of the control oscillator coupled thereto.

4. In a signalling system, a source of oscillations of controllable frequency, a source of oscillations of a first and substantially fixed frequency, a source of oscillations of a second and substantially fixed frequency, a source of oscillations of a third and substantially fixed frequency coupled to said first source for entraining the same for operation at its frequency, and a switching device controlled in accordance with signals for alternately connecting one or the other of said first two sources of oscillations of substantially fixed frequency to said source of controllable frequency for controlling the frequency of the oscillations generated in said source of controllable frequency in accordance with signals.

5. The method of signalling by frequency shift keying which includes these steps, producing oscillatory energy the frequency of which is readily variable, producing oscillations of a first and substantially fixed frequency, entraining said first mentioned oscillations by said second mentioned oscillations, generating oscillations of a second

and substantially fixed frequency higher than the frequency of said first oscillations of substantially fixed frequency, generating oscillations of a third and substantially fixed frequency lower than the frequency of the first mentioned oscillations of fixed frequency, entraining said oscillations of readily variable frequency alternately in accordance with said oscillations of second and third fixed frequency, generating signalling currents the characteristic of which alternates from a condition indicating mark to a condition indicating space and vice versa, and controlling the entraining of said oscillations of readily variable frequency by said oscillations of said second and third substantially fixed frequency in accordance with changes in the character of said signals.

6. In a frequency shift signalling system, a regenerative tube generator of controllable frequency, a source of oscillations of a first and substantially fixed frequency coupled with said generator for entraining the same lightly to operate at a first frequency, a second source of oscillations of substantially fixed frequency higher than said first frequency, a third source of oscillations of substantially fixed frequency lower than said first frequency, two electron coupling tubes each having input electrodes coupled respectively to said second and third sources of oscillations of substantially fixed frequency and having output electrodes coupled to said regenerative tube generator to alternatively entrain the same and control the frequency of operation thereof, a source of signals comprising energy keyed in amplitude between two values representing respectively mark and space signalling condition, connections between an electrode of each of said coupling tubes and a negative and a positive source of direct current potential, a switch in at least one of said connections to each of said electrodes, a relay cooperating with said switch and controlled by said signals for applying a negative potential to an electrode in one of said coupling tubes and a positive potential to an electrode in the other of said coupling tubes and vice versa as said signal energy is keyed between mark and space values or vice versa, and an output circuit coupled to said regenerative tube generator.

7. In a frequency shift signalling system, a regenerative generator of controllable frequency, said generator comprising an electron discharge device having an anode, a cathode and two grid-like electrodes, a circuit tuned substantially to the desired operating frequency coupling the anode, cathode and one of said grid-like electrodes in a regenerative oscillation generating circuit, resistive means coupling the other of said grid-like electrodes of said tube to the cathode thereof, a first source of oscillations of substantially fixed frequency coupled to said resistive means for entraining said regenerative generator to operate at the frequency thereof, a second source of oscillations of substantially fixed frequency different from the frequency of said last mentioned source of oscillations, an electron discharge coupling tube having input electrodes coupled to said last named source and having output electrodes coupled to the resistive means connected between said other grid-like electrode and the cathode of said first device, a source of signals which varies in magnitude between two values, one of which represents mark condition and the other of which represents space condition, a control electrode in said coupling tube, direct current supply circuits therefor including potential sources of different value, and switching means

for changing the value of the potential on said control electrode of said coupling tube, a relay associated with said switching means and coupled to said source of signals, and an output circuit coupled to said regenerative tube generator.
